UNITED STATES PATENT OFFICE.

CARL MUEHLEISEN, OF BERLIN, GERMANY, ASSIGNOR TO MERGENTHALER LINOTYPE COMPANY, A CORPORATION OF NEW YORK.

TYPOGRAPHICAL COMPOSING-MACHINE.

1,088,442.

Specification of Letters Patent. Patented Feb. 24, 1914.

Application filed June 26, 1913. Serial No. 775,834.

To all whom it may concern:

Be it known that I, CARL MUEHLEISEN, a citizen of the United States of America, residing at 23 Chausseestrasse, Berlin, N. 4, in the Empire of Germany, have invented new and useful Improvements in Typographical Composing-Machines, of which the following is a specification.

The invention relates to a typographical 10 composing machine having a fixed assembler entrance and a plurality of magazines pivotally arranged relatively to the said entrance, which magazines, by means of magazine entrances movable with them, are in 15 constant relation each with its respective distributor. When changing magazines in this kind of composing machine, the magazines must be moved relatively to the fixed assembler entrance in such a manner that 20 the relationship between the said magazines and the magazine entrances shall not be so disturbed as to interfere with the admission of the matrices into the magazines. The accurate admission of the matrices into 25 one or other of the magazines is secured, when the distance between the matrices hanging on the distributor bar and the partition or guide plates of the magazine entrance, is the same, or nearly the same, for 30 each position of the magazines. The invention described in my former Patent No. 1,081,952 dated July 9th, 1912, gave effect to this condition by arranging the pivotal axis about which each magazine, with its 35 magazine entrance, was capable of being turned, parallel with, and underneath, the respective distributor bar and in, or nearly in, the horizontal plane containing the upper edges of the guide plates of the magazine entrance.

In the just-named arrangement it was not found convenient for a pivot to be located at that end of the distributor mechanism at which it receives the matrices, for the 45 reason that the best position that the said pivot could occupy is already occupied by the distributor lift box or other adjacent parts of the distributor mechanism. The said pivot, according to the present invention, is therefore replaced by a curved guide or track which can be located beneath the aforesaid lift box, and which fulfils the same function as the said pivot.

Referring to the accompanying drawings:—Figure 1 is a right-hand side eleva-

tion and Fig. 2 a rear elevation, both partly in section, of part of a machine embodying the present improvements.

The two magazines 1, 2 have rigidly attached each to its right-hand upper end, a pivot 3, 4 respectively, free to rock in a stationary bracket or arm 5, Fig. 2; or the said pivots may be fast to the bracket 5 and the magazines be capable of being rocked relatively thereto. The magazines thus rock 65 about independent axes and therefore shift relatively to each other during their rocking movement.

Adjacent to the left-hand upper end of the magazines 1, 2, there are provided two 70 stationary segmental ways or tracks 6, 7 which may conveniently be formed on a single casting or bracket 8 secured to, or formed integral with the distributor bracket 9. The tracks 6 and 7 are concentric with the axes 75 of the pivots 3, 4 respectively, and consequently present different curvatures so as to permit the relative shifting of the magazines during their conjoint rocking movement. Each of the magazines 1, 2 or the frames 80 supporting the said magazines has a pair of rollers 10, 10 or 11, 11 pivotally mounted thereon and supported on the respective track 6 or 7.

When, with the foregoing arrangement, 85 the front ends of the magazines 1, 2, are swung upward or downward to bring either one of them into operative relation to the assembler entrance 13, the rollers 10, 11 travel over the tracks 6, 7 respectively, the said tracks exercising on the left-hand side of the magazines the same control as that exercised by the pivots 3, 4 on the right-hand side thereof, and this without in any way obstructing or interfering with the free delivery of the matrices to the distributor mechanism, by the matrix lifter 12, beneath which, as shown in Fig. 2, the tracks 6, 7 90 are located.

The two rollers 10, 10 or 11, 11 are preferably situated at an angle of 90° apart, so that there will always be one of them tending to prevent the respective magazine from moving longitudinally or forwardly and another of them tending to secure the upper 105 end of the said magazine against transverse or downward displacement.

The before described apparatus is capable of being considerably modified without departing from the spirit of the invention, for 110

example, the arrangement of the tracks 6, 7 and rollers 10, 11 may be practically reversed, rigid segmental shoes being provided on the magazines or magazine frames 5 and adapted to travel over rollers pivotally secured to the distributor bracket 9, or the said shoes may bear directly upon the tracks 6, 7.

Having described my invention, I declare that what I claim and desire to secure by Letters Patent is:

1. In a typographical machine, the combination of assembling devices to coöperate with a single magazine at a time, and a plurality of conjointly movable magazines, any selected one of which may be brought into operative relation thereto, the said magazines being mounted so as to be capable of pivotal movement about independent axes 20 while passing into and out of such operative position, a pivot supporting each magazine at one side and a stationary curved track concentric with the pivot supporting it at the other side.
2. In a typographical machine, the combination of assembling devices to coöperate with a single magazine at a time, and a plurality of conjointly movable magazines, any selected one of which may be brought 30 into operative relation thereto, the said magazines being mounted so as to be capable of pivotal movement about independent axes while passing into and out of such operative position, a pivot supporting each 35 magazine at one side, a stationary curved track concentric with the pivot, supporting it at the other side, and devices operatively connected to the magazine capable of traveling over the said track.
3. In a typographical machine, the combination of assembling devices to coöperate with a single magazine at a time, and a plurality of conjointly movable magazines, any selected one of which may be brought 40 into operative relation thereto, the said magazines being mounted so as to be capable of pivotal movement about independent axes while passing into and out of such opera-

tive position, a pivot supporting each magazine at one side, a stationary curved track 50 concentric with the pivot, supporting it at the other side, and rollers rotatably mounted on the magazine frame capable of traveling over the said track.

4. In a typographical machine, the combination of a magazine pivotally supported at one side, and a curved track or guide to support it at the opposite side.

5. In a typographical machine, the combination of a plurality of magazines movable conjointly to bring any selected one into operative position, and a curved supporting track or guide for each of the magazines, the curvatures of said tracks being different so as to permit relative shifting 65 of the magazines during their conjoint movement.

6. In a typographical machine, the combination of a plurality of magazines movable conjointly to bring any selected one into 70 operative position, the said magazines being pivotally supported at one side upon fixed independent axes, and curved tracks or guides, one for each magazine, to support the magazines at the opposite side.

7. In a typographical machine, the combination of a magazine mounted to turn about a fixed axis and pivotally supported at one side in said axis, and a fixed support for the opposite side of the magazine located 80 below said axis and upon which the magazine may slide during its turning movement.

8. In a typographical machine, a magazine mounted to turn about a fixed axis and 85 pivotally supported at one side, and a fixed support for the opposite side of the magazine upon which the magazine may slide during its turning movement.

In witness whereof I have hereunto set 90 my hand in the presence of two witnesses.

CARL MUEHLEISEN.
